UNITED STATES PATENT OFFICE.

HENRY ERICSSON, OF CHICAGO, ILLINOIS.

ADJUSTABLE SCAFFOLD.

1,168,868.

Specification of Letters Patent. Patented Jan. 18, 1916.

Application filed April 4, 1910. Serial No. 553,363.

To all whom it may concern:

Be it known that I, HENRY ERICSSON, a citizen of the United States, residing at Chicago, in the county of Cook and State of Illinois, have invented certain new and useful Improvements in Adjustable Scaffolds, of which the following is a description.

My invention relates to a portable staging or platforms for use in general construction or repair work, or in any situation where a secure and rigid temporary platform may be required, especially where it is desirable to adjust the height of the platform from time to time as the work progresses.

The object of my invention is to provide a device of the kind described which shall be rigid and secure in any position and one which may be adjusted as desired without interfering with the men or material upon the platform.

To this end my invention consists in the novel construction, arrangement and combination of parts herein shown and described and more particularly pointed out in the claims.

In the accompanying drawings wherein like or similar reference characters indicate like or corresponding parts: Figure 1, 30 is an end elevation of my device. Fig. 2, is a side elevation of one end of the same. Fig. 3, is a section taken substantially on line 3—3 of Fig. 2. Fig. 4, is a view similar to Fig. 1 showing a slightly modified 35 form of adjusting mechanism. Fig. 5, is a side elevation of one end of the device shown in Fig. 4. Fig. 6, is a section taken substantially on line 6—6 of Fig. 5. Fig. 7, is a fragmentary section taken substantially on line 7—7 of Fig. 4.

In the preferred form shown in the drawings, my device consists of a pair of similar guides 1 with a platform 2 positioned between them and slidably attached to each, 45 so that the height of the platform may be adjusted as desired.

As shown each guide 1, comprises a pair of substantially similar parallel bars 3 rigidly connected at both ends and adapted, 50 when in use, to stand in a substantially vertical position. For this purpose a foot 4 is provided at the lower end of each guide of suitable size and construction to afford a stable bearing for the platform and avoid 55 any tendency to rock or tip when a load is placed upon it. At the upper end of each

of the guides 1 the bars 3 are connected by a member 5 rigidly but preferably removably attached to each with one or more eyes or loops 6 provided so that if desired my 60 device may be suspended from above where the desired height of the platform is too great, or for any other reason it cannot be practically supported from below. The platform 2 may be of any desired form, size 65 or construction suitable for the purpose for which it is to be employed and may be slidably attached to the guides 1 in any convenient manner.

As shown a pair of vertical shoes or 70 slides 7 are provided for each bar 3 suitably spaced from each other to receive the bar between them and snugly fit against its side faces.

A pair of cross arms or supports 8 are 75 rigidly attached to the shoes 7 near their lower ends, suitably spaced from each other to bear upon the faces of the bars 3 to prevent length-wise movement of the platform. The arms 8 are each preferably of sufficient 80 length to receive the deck or floor 9 of the platform which is preferably rigidly but removably secured thereto to rigidly connect the guides 1 at opposite ends of my device. The upper ends of the shoes 7 are also rigidly connected the same as the lower ends by a pair of members 10—10 which, if desired, may be employed as supports for a supplemental platform or table 11 as shown, 85 so that material or supplies may be conveniently positioned upon the supplemental table for use when required without encumbering the main platform. Any suitable means may be provided to adjust and control the position of the platform 2. As 90 shown, in Figs. 1, 2 and 3 a suitable winch 12 is mounted upon the shoes 7 with a removable crank 14 or other convenient means arranged to operate the same. A pair of pulleys or sheaves 15 and 16 or equivalent 95 means are secured to the member 5 and cross pieces 10 of the platform respectively so that a rope or other suitable flexible member 17 may be rove through the blocks with one end attached to the member 5 as shown and the free end leading to the drum of the winch 12 so that the winch may be operated to adjust the position of the platform upon the guides and maintain the same in its adjusted position.

In the form shown in Figs. 4, 5, 6 and 7, the guides and platforms are substantially

the same as hereinbefore described. The adjusting mechanism however consists of a substantially horizontal shaft 20 mounted in suitable bearings 21—21 upon the shoes 7. 5 5 A pinion 22 is rigidly secured to the shaft 20 for each bar 3 and a rack 23 adapted to co-operate with the respective pinions is rigidly secured to each bar, in position to mesh with the pinions so that by rotating the 10 shaft 20 the platform 2 will be moved vertically upon the guides.

Any suitable means may be provided to operate the shaft 20. As shown a ratchet wheel 24 is rigidly secured to the shaft near 15 one end and a lever 25 is rotatably mounted upon the shaft with a spring actuated pawl 26 arranged to engage the teeth of the ratchet so that by oscillating the free end of the lever the shaft will be rotated. A pair 20 of pawls 27—27 are also provided to engage the pinions 22—22 to prevent their rotation in a reverse direction and thereby maintain the platform in its elevated position. In the form shown, also a pair of spring actuated dogs or pawls 28—28 are provided upon 25 the platform of each guide 1, each dog being arranged to engage the teeth upon one of the racks 23 as an additional lock to support the platform in its elevated position. 30 The operation of my device is obvious and no further description of the same is believed to be necessary.

Having thus described my improvement it is obvious that various immaterial modifications may be made in my device without departing from the spirit of my invention hence I do not wish to be understood as limiting myself to the exact form or construction shown.

40 What I claim as new and desire to secure by Letters Patent is:

1. A device of the kind described, comprising a platform, a vertical guide positioned at each end of said platform, each 45 comprising a pair of substantially independent parallel bars and a plurality of substantially independent shoes mounted upon said platform and engaging said guides to direct said platform and maintain the same in position, in combination with independent means for each guide mounted upon and extending between the shoes for said guide

and arranged to co-operate with means upon said bars for adjusting and controlling the vertical position of said platform. 55

2. A device of the kind described, comprising a platform, a vertical guide positioned at each end of said platform, each comprising a pair of substantially independent parallel bars one near each corner of said platform and a plurality of substantially independent shoes mounted upon said platform and engaging each guide to direct said platform and maintain the same in position, in combination with independent means for each guide mounted upon and extending between the shoes for said guide and arranged to co-operate with means upon said bars for adjusting and controlling the vertical position of said platform. 60 65 70

3. In a scaffold a plurality of platforms, a guide for each end of said platforms, each comprising a pair of substantially parallel bars each positioned near the corner of said platforms, and a pair of shoes secured to and rigidly connecting said platforms and engaging said bars to direct said platforms and maintain said platforms in position, in combination with mechanism mounted upon said shoes and extending between said bars for controlling the position of said platforms. 75 80 85

4. A device of the kind described, comprising a plurality of connected substantially parallel platforms a vertical guide for each end of said platforms consisting of a substantially independent bar positioned near each corner of the smaller of said platforms substantially independent shoes extending between and rigidly secured to said platforms for rigidly connecting the platforms and engaging each guide to direct said platforms, in combination with independent means mounted jointly upon and extending between said shoes for each pair of bars arranged to co-operate with means upon said bars for adjusting and controlling the position of said platform. 90 95

In testimony whereof, I have hereunto signed my name in the presence of two subscribing witnesses.

HENRY ERICSSON.
